Primary Examiner — Joseph Kukella*Assistant Examiner* — Heather Wencl(74) *Attorney, Agent, or Firm* — Dhiraj Jindal; PATENT YOGI LLC(57) **CLAIM**

The ornamental design for a levitation device, as shown and described.

DESCRIPTION

FIG. 1 is a top view of a levitation device showing my new design;

FIG. 2 is a bottom view thereof;

FIG. 3 is a front view thereof;

FIG. 4 is a rear view thereof;

FIG. 5 is a left side view thereof;

FIG. 6 is a right side view thereof;

FIG. 7 is a top perspective view thereof; and,

FIG. 8 is a bottom perspective view thereof.

The broken lines in the drawings depict portions of a levitation device and form no part of the claimed design.

1 Claim, 8 Drawing Sheets(56)
